(57) **CLAIM**

The ornamental design for a portable kitchen, as shown and described.

DESCRIPTION

FIG. 1 is a front, top, and left-side perspective view of a portable kitchen showing the new design;

FIG. 2 is a rear, bottom, and right-side perspective view thereof;

FIG. 3 is a left side elevation view thereof, the right side elevation view is a mirror image of the left side elevation view, and is not shown;

FIG. 4 is a front elevation view thereof;

FIG. 5 is a rear elevation view thereof;

FIG. 6 is a top plan view thereof; and,

FIG. 7 is a bottom plan view thereof.

The broken lines shown in the drawings are for illustrative purposes only and form no part of the claimed design.

1 Claim, 7 Drawing Sheets
